UNITED STATES PATENT OFFICE.

FRANK M. WOJCIECHOWSKI, OF ATTLEBORO, MASSACHUSETTS, ASSIGNOR TO MARATHON COMPANY, OF ATTLEBORO, MASSACHUSETTS, A CORPORATION OF MASSACHUSETTS.

DESIGN FOR A VANITY CASE OR SIMILAR ARTICLE.

Application filed April 3, 1926. Serial No. 17,175. Term of patent 7 years.

To all whom it may concern:

Be it known that I, FRANK M. WOJCIECHOWSKI, a citizen of the United States of America, residing at 78 Grant Street, in the city of Attleboro, county of Bristol, and Commonwealth of Massachusetts, have invented a new, original, and ornamental Design for a Vanity Case or Similar Article, of which the following is a specification, reference being had to the accompanying drawing, forming a part thereof.

In said drawing:

Fig. 1 is an obverse view of a vanity case showing my new design; and

Fig. 2 is a reverse view thereof.

The handle of the case is of the ordinary chain link type which is extended continuously throughout the dotted line portion of the handle.

I claim:

The ornamental design for a vanity case or similar article substantially as shown.

Signed by me at Attleboro, in the county of Bristol and Commonwealth of Massachusetts, this 25 day of March, 1926.

FRANK M. WOJCIECHOWSKI.
